UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,838, dated November 5, 1895.

Application filed September 30, 1895. Serial No. 564,224. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of Florentine style of ornaments placed at certain distances apart over the surface of the paper, as represented in the accompanying drawing.

The border of the design is formed of similar ornaments of Florentine style, with ornate

mental scrolls extending from the base of said ornaments and connected with small Florentine style of ornaments, as shown in the drawing.

What I claim is—

1. The design for wall paper herein shown and described.
2. In the design for wall paper, the border herein shown and described.

Witness my hand this 27th day of September, 1895.

CHARLES BOOZ.
